W. H. CLOWRY,
INTERNAL COMBUSTION ENGINE,
APPLICATION FILED FEB. 14, 1921.

Patented Oct. 31, 1922.

FIG. 1.

FIG. 2.

William H. Clowry, Inventor.

Patented Oct. 31, 1922.

1,434,093

UNITED STATES PATENT OFFICE.

WILLIAM H. CLOWBY, OF CHICAGO, ILLINOIS.

INTERNAL-COMBUSTION ENGINE.

Application filed February 14, 1921. Serial No. 444,889.

To all whom it may concern:

Be it known that I, WILLIAM H. CLOWRY, a citizen of the United States, residing at Chicago, in the county of Cook and State 5 of Illinois, have invented new and useful Improvements in Internal-Combustion Engines, of which the following is a specification.

This invention relates to internal combustion engines, and its object is to provide 10 a novel and improved arrangement of inlet and exhaust ports whereby a thorough scavenging action, with a consequent greater efficiency, is obtained.

15 In order that the invention may be better understood, reference is had to the accompanying drawing, forming a part of this specification in which,

Figure 1 is a central longitudinal section of the cylinder of the engine showing 20 the arrangement of inlet and exhaust ports, and Fig. 2 is a horizontal section on the line 2-2 of Fig. 1.

Referring specifically to the drawing, 5 25 notes the cylinder of the engine, and 6 the piston therein, the latter being shown at the end of the firing stroke.

In the head of the cylinder 5 is an inlet port 7, and in the side wall of the cylinder 30 are exhaust ports 8, these ports being positioned such a distance from the cylinder head as to be uncovered by the piston 6 at or near the end of its firing stroke. The port 7 is provided with a valve 9 operated 35 automatically by suction or by any suitable mechanism to open at or near the end of the firing stroke of the piston to admit a fresh charge to the cylinder, which is compressed on the return stroke of the piston, the valve 40 9 in the mean time having closed.

The ports 8 extend in a circular series 45 completely around the cylinder 5, and the latter is formed exteriorly with a spacious chamber 10 into which said ports discharge.

A pipe 11 is connected to the chamber 45 50 10 to carry the exhaust gases away. The large number of exhaust ports permits the spent gases to quickly pass out of the cylinder, and the cylinder is therefore well scavenged.

The outer end of the pipe 11 is provided

with a hinged and weighted lid 12, which is pushed open by the exhaust gases, but remains shut to prevent the entrance of air, which would weaken the fuel mixture in the cylinder.

55

The ports 8, while shown circular in shape may be made square as indicated by fine dotted lines or in any other form best suited to the purpose. Also the distance of the ports from the end of the piston stroke 60 may be varied to secure the best results from the particular type of engine.

The engine will not operate with a full throttle at low speed without the valve, for the reason that the vacuum is destroyed by 65 air entering the cylinder through the exhaust ports, thus preventing fuel charges from entering the cylinder. Again, without the valve, the engine will not start because on the suction stroke, when the piston uncovers 70 the exhaust ports, air is drawn in through the latter, thinning the mixture too much. At high speeds, the valve remains open, the successive explosions occurring at such short intervals that there is not sufficient time 75 for the valve to close. At low speed, the valve is closed by the vacuum in the cylinder which varies as the force of the explosion, and this vacuum reloads the cylinder 80 through the intake by the action of the closed valve 12. The back pressure resulting from the valve is negligible, and pre-ignition will not occur unless too stiff a spring is used.

85

I claim:

In an internal combustion engine, a cylinder, and a piston therein, the cylinder having a valve-controlled inlet port at its rear end, and exhaust ports at its forward end which are uncovered by the piston at or 90 near the end of its firing stroke, said exhaust ports extending in a circular series around the cylinder, and a chamber on the outside of the latter into which said ports discharge, said chamber having an outlet valve adapted to open for discharge only.

In testimony whereof I affix my signature.

WILLIAM H. CLOWRY.
